UNITED STATES PATENT OFFICE.

STEPHEN PORTER, OF BOSTON, MASSACHUSETTS.

DOOR-PLATE.

SPECIFICATION forming part of Letters Patent No. 311,782, dated February 3, 1885.

Application filed December 22, 1883. (Model.)

To all whom it may concern:

Be it known that I, STEPHEN PORTER, of Boston, in the county of Suffolk and State of Massachusetts, have invented certain new and 5 useful Improvements in Door-Plates, of which the following is a full, clear, and exact description.

This invention relates to a new method of securing name-plates to doors of dwelling-houses, buildings, &c.; and the invention consists in constructing and arranging devices for securing name-plates to doors, &c., substantially as hereinafter fully described, reference being had to the accompanying plate 15 of drawings, in which—

Figure 1 is a front view of a name-plate constructed and arranged to be applied and secured to a door of a building, &c., according to this invention. Fig. 2 is a front view 20 with the frame of the name-plate removed. Fig. 3 is a detail transverse section, enlarged, of a door of a building with a name-plate attached thereto in longitudinal section on line 33, Fig. 1. Fig. 4 is a plan view of the under 25 side of the frame of the name-plate.

In the drawings, A represents a plate of sheet metal or other suitable material, having ear-pieces B, by which it is secured to the door by screws C. This plate A has sides 30 D and ends E projecting outwardly therefrom, forming, as it were, a shallow box, in which is placed a plate, F, of metal or wood, or of any suitable material, on the outer surface of which is engraved, cut, or printed, in 35 suitable manner, the name of the person, &c., desired, and over the plate F is placed a plate, G, of transparent material, such as glass.

H is a frame of the shape shown, and preferably of metal, its inner edges, J, extending 40 over and slightly beyond the sides D and ends E of plate A sufficiently for said frame to hold the plate F and glass G securely therein, the frame also being wide enough to extend over and cover the ear-pieces B, and 45 hiding them from view.

From one of the ends E of the plate A, projecting outwardly therefrom, is a flat rib or tongue, K, set back so as to leave a space, L, between it and the face *a* of the plate A, and 50 on the opposite end E is a rib or bar, P, hav-

ing its outer edge preferably rounded, as shown, which rib is also set back from the face *a* of the plate A.

On the inner side of one end of the frame H is a flat rib or tongue, M, extending as 55 shown, and on the opposite end is a spring-rib, R, bent in the form shown in cross-section in Fig. 3 more particularly.

To attach the name-plate to the door, first 60 secure the plate A to the door by screws C, and then place the rib M of frame H under the rib K (between it and the door) of the plate A, and then pressing the frame at its other end toward and against the plate A with sufficient pressure to force the spring R, by its 65 edge Q, around the edge of and under the rib P of the plate, which secures the frame H to the plate A, and thus the whole to the door, as shown more particularly in Fig. 3.

To remove the name-plate, insert a thin strip 70 of metal under the edge of the end S of the frame and force the spring from under the rib P, and then raise said end S sufficiently for it to clear the outer edges of the end E, and push the frame H toward the other end 75 of the plate A, which will remove the rib M of the frame from under the rib K of the plate, thus freeing the frame, when the plate A can be removed by unscrewing the screws C.

By attaching a name-plate to a door according to this invention, holes or a pin or wire extending through the door are obviated, which are not only objectionable as to appearance, but the pins are liable to tear the clothing of persons, and as no means of securing the name-plate are in sight, the door is practically not marred in appearance. The edges of the plate A and between them and the glass G can be filled and covered with cement to prevent water entering therein to 85 injure or destroy in any way the same. The plate A need not have sides D and ends E, as the frame itself can be suitably constructed to hold the plate F and glass G in place. Also, the ear-pieces B can be dispensed with, and 90 the plate A secured by screws through its central portion, which in many cases might be preferable. Also, it can be in two pieces, one to each of its ribs K P; or the said ribs 95 can be attached in any suitable manner di- 100

rectly to the door independent of each other and without any plate connecting them together.

Having thus described my invention, what I claim, and desire to secure by Letters Patent, is—

1. In a name-plate for a door, a frame, H, having rib M and spring R, in combination with ribs K and P, secured to the door, for the purpose specified.

2. In a name-plate for a door, a frame, H, having rib M and spring R, in combination with a plate, A, adapted to be secured to the door, and having ribs K and P, for the purpose specified.

3. In a name-plate for a door, a frame, H, having rib M and spring R, in combination with a plate, A, adapted to be secured to the door, and having sides and ends D E and ribs K and P, substantially as and for the purpose specified.

In testimony whereof I have hereunto set my hand in the presence of two subscribing witnesses.

STEPHEN PORTER.
